UNITED STATES PATENT OFFICE.

ETHAN I. DODDS, OF CHICAGO, ILLINOIS, ASSIGNOR TO THE PULLMAN COMPANY, OF CHICAGO, ILLINOIS, A CORPORATION OF ILLINOIS.

DOOR-OPERATING MECHANISM FOR DUMPING-CARS.

No. 874,578.

Specification of Letters Patent.

Patented Dec. 24, 1907.

Original application filed July 24, 1906, Serial No. 270,893. Divided and this application filed July 1, 1907. Serial No. 381,662.

To all whom it may concern:

Be it known that I, ETHAN I. DODDS, a citizen of the United States, residing at Chicago, in the county of Cook and State of Illinois, have invented certain new and useful Improvements in Door-Operating Mechanism for Dumping-Cars, of which the following is a specification.

My invention concerns the door actuating devices for dumping cars, its object being to provide a construction free from chains which are likely to become kinked and broken, and one which is positive in its action and easy to operate, the strains on the operating shaft being substantially balanced or neutralized.

A further aim and purpose of my invention is to securely lock the dumping doors in closed position with but little if any tendency to open, even though none of the usual locking means for preventing the operating shaft from turning are employed. As a safeguard, however, such a lock would ordinarily be used and, as is customary, it would be located at the end of the car.

On the accompanying drawings, forming a part of this specification, I have illustrated my new invention, like reference characters referring to the same parts throughout the views.

On these drawings Figure 1 is a sectional perspective view of a car showing the dumping doors in open position; and Fig. 2 is a similar view with the doors closed.

The car underframe includes a pair of channel center sills 1, 1 and a pair of similar side sills 5, 5. The car body comprises the sides 7, 7 which are fastened to the side sills 5, 5 by side stakes 6, I-shaped in cross-section, interposed between the side sills and the outer faces of the side walls 7. A hood formed of a pair of inclined plates 15 fits over the center sills 1, 1 and deflects the load on either side thereof. The bottom of the car is composed in part by downwardly-divergent floor plates 19 fastened to the bottom flanges of the center sills 1, 1 and in part by the hinged doors 22 hinged at 23 to the sides 7 beneath the side sills 5, and stiffened and strengthened by longitudinal angle bars 24 riveted thereto. Extended longitudinally of the car beneath the center sills and rotatable in suitable bearings (not shown) is a shaft 26 having fixed thereto an arm 33 with a hub 33^b or sleeve 33^b surrounding the shaft. This

arm which rotates with the shaft is connected by a straight link 34 with one end of a curved, arcuate, or substantially semi-circular link 35 having an internal diameter substantially equal to the external diameter of hub or sleeve 33^b. The other end of the curved link 35 is connected to the free edge of one of the doors 22 at 37 by a link 36 pivoted to the door and link. Also fastened to the shaft 26 so as to rotate therewith is an arm 33^a having a hub 33^c encircling the shaft, the arms 33 and 33^a being spaced 180 degrees apart. Arm 33^a is connected to the other door 22 at 41 by straight links 38 and 40 and a curved link 39 substantially like parts 34, 35 and 36, except that the curved or arcuate link 39 is bowed upwardly instead of downwardly so that it may engage, fit over, and conform to the curvature of hub 33^c.

When the doors are in their open position, as indicated in Fig. 1, the straight and curved links occupy the positions shown, and when it is desired to close the doors shaft 26 is rotated by any suitable means (not shown) in such a direction that the arms 33 and 33^a move away from the hinges 23 of the dumping doors 22.

It will be noticed that the links 34 and 38 are of substantially the same length as arms 33 and 33^a, whereby as the latter arms rotate and reach a certain position, the curved links engage the hubs of the corresponding arms and rotate therewith until the arms 33 and 33^a assume the positions indicated in Fig. 2, in which disposition of the parts the points of pivotal connection between the arms 33 and 33^a with their links are substantially in right lines between the axis of the shaft and the pivotal connection of the links with the doors.

It will be noticed that when the doors are in the closed position, with the load above them resting thereon, the pull on the curved links 35 and 39 is very close to the axis of the shaft 26, and these opposite strains on the shaft are substantially balanced and neutralize each other. The strains put upon the curved links 35 and 39 by the loads on the doors are only partially transmitted to the arms 33 and 33^a fixed to the shaft, the remainder being counteracted and overcome by the friction between the curved links and the hubs 33^b and 33^c over which they fit.

Whatever portions of the strains actually

reach the arms 33 and 33^a have but little tendency to turn the shaft owing to the fact that the arms are nearly on dead center and the links connected thereto lie close to the shaft. The doors, therefore, are securely locked closed and at the same time there is only small strain on the shaft either to move it bodily laterally or to turn it in its bearings.

10 To those acquainted with this art it will be apparent that as many of these door operating mechanisms as is desired or necessary may be used for each pair of doors, and that if the car has a plurality of dumping doors on each side of its center sills each door will be connected to the operating shaft by at least one system of links.

15 I have herein disclosed a mechanism for opening and closing the dumping doors of a car by which the strains on the doors, although transmitted to the shaft to some extent, are practically balanced and neutralized. Of course, minor modifications may be made in the structure shown and 20 described without departure from my invention as outlined by the appended claims.

25 This application is a division of my pending application, Serial No. 270,993, for metallic ore cars.

30 I claim:

1. In a railway car, the combination of a dumping door, and an operating mechanism therefor including a rotary shaft, an arm fixed thereto and rotatable therewith, 35 a curved link, means connecting one end of said curved link to the door, means connecting the other end of said curved link to said arm, said last-mentioned connecting means and curved link being adapted to 40 embrace said shaft in the closed position of said door, substantially as described.

2. In a railway car, the combination of a dumping door, and an operating mechanism therefor including a rotary shaft, an 45 arm having a hub or sleeve fastened on said shaft, an arcuate link the internal diameter of which is substantially equal to the external diameter of said hub or sleeve, means connecting one end of said arcuate 50 link to said arm, and means joining the other end of said arcuate link to said door, said arcuate link during a portion of the closing of said door fitting over said hub or sleeve and turning therewith, substantially 55 as described.

3. In a railway car, the combination of a dumping door, and an operating mechanism therefor, including a rotary shaft, an arm fixed thereto and rotatable therewith, 60 a substantially semi-circular link, means connecting one end of said semi-circular link to said door, and means connecting the

other end of said semi-circular link to said arm, said last-mentioned connecting means and link being adapted to embrace said shaft in the closed position of said door with the end of said arm between said shaft and door, substantially as described.

4. In a railway car, the combination of a pair of dumping doors, a rotary shaft, an operating mechanism for each of said doors including an arm fixed to said shaft and rotatable therewith, a curved link, means connecting one end of said curved link to its door, and means connecting the other end of said curved link to said arm, said last-mentioned connecting means and curved link being adapted to embrace said shaft in the closed position of said door, said arms projecting in opposite directions from said shaft, substantially as described.

5. In a railway car, the combination of a pair of dumping doors, a rotary shaft, and an operating mechanism for each of said doors including an arm having a hub or sleeve fastened on said shaft, an arcuate link, the internal diameter of which is substantially equal to the external diameter of said hub or wheel, a link connecting one end of said arcuate link to said arm, and means joining the other end of said arcuate link to its door, said arcuate link during a portion of the closing of said door fitting over said hub or sleeve and turning therewith, said arms projecting in opposite directions from said shaft, substantially as described.

6. In a railway car, the combination of a door, a shaft, an arm fixed to said shaft, and a series of links connecting an end of said arm to said door, said links being adapted to embrace said shaft with the end of said arm substantially in a right line between said shaft and the pivotal point of attachment of said links to said door when the latter is in closed position, substantially as described.

7. In a railway car, the combination of a pair of dumping doors, an operating shaft, a pair of arms fixed to and extended in opposite directions from said shaft, and a series of links connecting an end of each of said arms to its door, said links being adapted to embrace said shaft with the ends of said arms substantially in right lines between said shaft and the pivotal points of attachment of said links to said doors when the latter are in closed position, substantially as described.

ETHAN I. DODDS.
